CLAIM

The ornamental design for a protector for a wrist watch lens or the like, as shown and described.

DESCRIPTION

FIG. 1 is a front view of a protector for a wrist lens or the like showing my new design; the broken lines showing the user's hand and wrist watch or the like are for illustrative purposes only, and form no part of the claimed design; FIG. 2 is a top elevational view of my new design; the broken lines showing the wrist watch or the like are for illustrative purposes only, and form no part of the claimed design;

FIG. 3 is a bottom view of my new design; the broken lines showing the wrist watch or the like are for illustrative purposes only, and form no part of the claimed design; FIG. 4 is a first side view of my new design; the broken lines showing the wrist watch or the like are for illustrative purposes only, and form no part of the claimed design; FIG. 5 is a second side view of my new design; the broken lines showing the wrist watch or the like are for illustrative purposes only, and form no part of the claimed design; FIG. 6 is a rear view of my new design; the broken lines showing the wrist watch or the like are for illustrative purposes only, and form no part of the claimed design; and, FIG. 7 is a front view of my new design; the broken lines showing the wrist watch or the like are for illustrative purposes only, and form no part of the claimed design.
